UNITED STATES PATENT OFFICE.

WALTER J. PARLE, OF PONTIAC, MICHIGAN.

MULTIPLE-DOOR BOLT.

No. 922,325.

Specification of Letters Patent.

Patented May 18, 1909.

Application filed October 13, 1908. Serial No. 457,504.

To all whom it may concern:

Be it known that I, WALTER J. PARLE, a citizen of the United States, residing at Pontiac, in the county of Oakland and State 5 of Michigan, have invented new and useful Improvements in Multiple-Door Bolts, of which the following is a specification.

This invention relates to locks for single or double swinging or sliding doors, the object of the invention being to provide a simple and effective locking mechanism which possesses certain novel features of construction and material advantages in operation as hereinafter fully described and claimed.

15 In the accompanying drawing,—Figure 1 is an inner elevational view, parts being broken away, showing the application of the invention to an outwardly swinging door. Fig. 2 is an irregular vertical longitudinal 20 section of the same. Fig. 3 is an outer or rear elevational view of the upper keeper and trip device.

Referring to the drawing, 1 designates a door, which in the present illustration, is designed to represent an outwardly swinging door. The inner face of this door is provided 25 with sockets or recesses 2, 3, and 4, respectively, covered by slotted wear plates 5, 6, and 7 suitably fastened to said face of the 30 door. The recesses 2 and 3 are arranged at or near the upper and lower edges of the door and adjacent to the free side or swinging edge thereof, while the recess 4 may be disposed at any intermediate point between the 35 same.

8 may represent the side of the door frame opposite the side to which the door 1 is hinged or pivoted or it may represent a companion swinging door in a double-door construction, as hereinafter described.

Secured to the ceiling or top of the door frame above the door opening is a keeper comprising a bracket plate 9 having spaced depending arms 10 and 11, which support 45 an intermediately arranged horizontal keeper pin 12. The arm 10 and adjacent portion of the pin are arranged on the inner side of the door opening and in the path of the door, as shown. A similar keeper is secured to the 50 floor or sill of the door frame and comprises a bracket 13 having spaced uprightly extending arms 14 and 15 which support a horizontal keeper pin 16. The arm 14 and adjacent portion of the pin 16 are also arranged on the inner side of the door opening.

and in the path of the door. When the door is closed, the faces of the plates 5 and 6 abut against these keeper brackets 9 and 13 and form therewith stops to limit the closing movement of the door and hold the same 60 firmly against further inward movement.

Corresponding swinging bolts 17 and 18 are pivotally mounted at their inner ends upon transverse pins 19 and 20 in the recesses 2 and 3 and project outwardly through the 65 slots in the plates 5 and 6. These bolts are provided with downwardly projecting hooked outer ends 21 to engage the pins 12 and 16, said hooked ends being formed with a curved or beveled contact face 22. The pins 12 and 70 16 are preferably in the form of rollers journaled to rotate in the keeper brackets to facilitate the engagement and disengagement of the hooks therewith and therefrom and to reduce the resulting friction. Coiled 75 contractile springs 23 and 24 are arranged in the respective recesses 2 and 3 and are connected with the pivoted ends of the bolts to throw the hooked locking ends thereof downward into normal locking position. Each of 80 these springs is secured at one end to a crank lug or projection 25 on the pivoted end of the bolt and at its other end to an attaching lug or projection 25 on the associated wear and stop plate. 85

When the door is swung to a closed position, the curved or beveled contact surfaces 22 of the bolts contact with the outer sides of the pins 12 and 16 and ride up on said pins under the swing of the bolts on their pivots 90 against the resistance of the springs, which are expanded, and then snap down into engagement with the inner faces of said pins under the contraction of the springs, thus rendering the locking action automatic. At 95 the instant the bolts come into locking engagement with the pins the plates 5 and 6 abut squarely against the brackets 9 and 13, whereby the door will be held firmly at top and bottom against play in either direction. 100 The vertical slots in the plates 5 and 6 through which the bolts project are of such length as to permit the bolts to have just the required amount of pivotal movement, the upper walls of the slots acting as stops to 105 allow the bolts to pass easily over the keeper pins as the door begins its opening and concludes its closing movement, while the lower end walls of the slots serve as stops to prevent downward movement of the bolts 110

beyond their normal horizontal locking position. The bolts will thus be supported and reinforced by the plates at all times except when they are swinging into and out of engagement with the keeper pins, thus adding to the strength and stability of the fastening, while at the same time relieving the springs 23 and 24 of strain.

The bolts are pivotally connected for movement in unison by a rod 27 which is preferably composed of sections coupled by a turn buckle 28, by which the rod may be adjusted as to length to insure an accurate action of the bolts and to compensate for other conditions requiring relative adjustment of the bolts. An operating lever 29 is pivoted at one end on a pin 30 within the recess 4 and projects through the slot in the wear plate 7. This lever is intermediately pivoted to the rod 27 by a pin or stud 31 and is provided at its opposite or outer end with a lateral handle 32. By a lifting motion of this lever the hooked locking bolts may be raised out of engagement with the keeper pins to unlock the door and permit it to be swung open, the parts being returned to normal or locking position upon the subsequent release of the lever by the gravity of their weight and the action of the springs. When the part 8 is a companion door to door 1 in a double-door construction, it will be understood that said door 8 will be provided with a corresponding set of locking devices, the hooks of which may engage the same, keepers 35 or an independent set of keepers to independently lock said door 8 in closed position. In the drawings, however, I have shown the keepers of proper size and arrangement to be engaged by the locking hooks of both doors, 40 from which it may be understood that a double-door structure is intended to be illustrated, the locking mechanism being omitted from door 8 in order to prevent the confusion and obscurity liable to arise from the illustration of a complexity of parts.

From the foregoing description, the construction and mode of operation of the locking mechanism will be readily understood, and it will be seen that the closed door will be firmly and securely fastened at top and bottom in such a manner as to prevent any play or spring thereof. When the locking mechanism is arranged on the inner side of an outwardly swinging door, as shown, no part of the lock will be exposed on the outside of the door, so that the door can not be opened except by a person on the inside of the apartment closed by the door or by one passing into said apartment from the exterior 55 through an auxiliary door. Moreover, no preliminary adjustments are required to lock the door, as it may be locked by simply pushing or pulling it to closed position. Should either spring break, the other one would still 60 hold the bolts locked, or should both springs

break at the same time, an improbable occurrence, the weight of the locking elements would still maintain them in locking position by gravity.

By suitable modifications of the keepers, the lock can be made to work on a door that swings outward or inward or on a sliding door, and by extending the operating lever through the door the latter may be opened from either side. I have not deemed it necessary to show these modifications, as they are such as fall within the scope of the invention and skill of the mechanic and do not vary the principle of operation of the invention.

In connection with the locking mechanism for each door, I provide a trip or releasing device whereby the locking means may be released from a distant point, thus rendering the lock of peculiar value for use on the doors of fire stations or engine houses to enable the same to be quickly unlocked when the fire apparatus is ready to go out in response to an alarm. This trip or release device is mounted upon the upper keeper 9 and comprises an angle or bell-crank lever 33 embodying an operating arm 34 and a trip arm 35. These arms are connected at their point of intersection by a hub or sleeve 36 through which passes a rod 37 journaled to rotate at its ends in the bracket arms 10 and 11 and to which said sleeve is fixed by a pin or key 38. The arm 35 is provided with a hooked extremity 39 to engage the keeper pin 12 and limit the swinging movement of the lever in its releasing action, the lever being retained in normal position and returned to such position after actuation by a spring 40 connecting the arm 34 with the bracket. On the arm 35 is a sleeve 41 through which passes a contact pin 42 projecting laterally beyond both sides of the lever to provide latch engaging members 43 adapted to engage the beveled faces of the upper locking hooks of both doors 1 and 8. The arm 34 is formed with an eye 44 for connection with an operating rope, chain or cable (not shown) which may extend to any suitable point in the engine house for operation. By pulling on this rope or cable the lever will be actuated to raise and release the latches in an obvious manner, allowing the doors to be opened, and upon release of said rope the spring 40 will return the lever to normal position. It will be observed that the trip device does not in any way interfere with the operation of the latch, and will automatically reset itself for operation, and its advantages in use for the purpose described will be apparent.

Having thus fully described the invention, what is claimed as new is:—

1. In a door lock, a keeper having spaced arms, a pin extending between the arms, a door carrying a spring actuated bolt having a hooked end beveled to slide over and into

engagement with said pin, a pivoted automatically-retracted trip device mounted on the keeper for engaging the beveled portion and retracting the bolt, and means for operating said trip device.

2. In a door lock, the combination of upper and lower keepers, each embodying a bracket having spaced arms and a pin extending transversely between the arms, a door, spring actuated bolts pivoted to the door and having beveled hooked ends to ride over and snap into engagement with said pin, a rod connecting the bolts for movement in unison, a retracting lever pivotally connected with the door and rod, a pivoted automatically-retracted trip device mounted on the upper keeper and adapted to engage the beveled portion of the associated latch to retract the same, whereby the latches may be retracted independently of the lever, and means for operating said trip device.

3. In a door lock, the combination of upper and lower keeper brackets, a door provided with recesses, slotted plates covering said recesses and adapted to abut against said keeper brackets to limit the closing movement of the door, bolts pivotally mounted within the recesses and extending through the slots in the plates and provided at their outer ends with hooks to engage the keepers, the lower end walls of the slots of the plates forming stops to limit the downward movement of the bolts, springs within the recesses and acting upon the pivoted ends of the bolts to throw the hooked ends thereof downward, a rod connecting the bolts for movement in unison, and an operating device connected with said rod.

4. In a door lock, the combination of upper and lower keeper brackets, each having spaced arms and a locking pin extending between the arms, a door provided with recesses, slotted plates covering said recesses and adapted to abut against said keeper brackets to limit the closing movement of the door, bolts pivotally mounted within the recesses and extending through the slots in the plates and provided at their outer ends with hooks to engage the locking pins of the keepers, the lower end walls of the slots of the plates forming stops to limit the downward movement of the bolts, springs within the recesses and acting upon the pivoted ends of the bolts to throw the hooked ends thereof downward, a rod connecting the bolts for movement in unison, and an operating device connected with said rod.

5. In a door lock, a keeper, a door, a pivoted latch upon the door to interlock with the keeper, a trip device pivotally mounted on the keeper to engage and release the

latch, and means for automatically resetting said device after operation.

6. In a door lock, a keeper provided with a keeper pin, a door, a pivoted hooked latch on the door to engage said pin, a trip lever pivotally mounted upon the keeper and having an operating arm and a trip arm, the latter being provided with a projection to engage and release the latch and a stop portion to engage the pin, and a spring acting on said operating arm to retract and automatically reset said lever.

7. In a door lock, the combination of upper and lower keeper brackets, a door provided with recesses, slotted plates covering said recesses, bolts pivotally mounted within the recesses and extending outwardly through the slots in the plates and provided at their outer ends with hooks to engage the keepers, the lower end walls of the slots of the plates forming stops to limit the downward movement of the bolts, a rod connecting the bolts for movement in unison, spring means for projecting the bolts, and an operating device connected with said rod.

8. In a door lock, a keeper pin, a door, a pivoted hooked latch on the door to engage said pin, and a spring retracted latch lever provided with a trip arm to engage and release the latch and a stop portion to engage the pin.

9. In a door lock, a keeper having spaced arms, a pin extending between the arms, a door carrying a spring actuated bolt having a hooked end beveled to slide over and into engagement with said pin, a trip device comprising a lever pivotally mounted on the keeper and having an operating arm and a retracting arm, the latter being provided with a contact portion to engage the beveled face of the bolt and a stop portion to engage the pin, a spring for retracting said device, and actuating means therefor connected with said operating arm.

10. In a door lock, the combination of upper and lower keepers, pivoted hooked bolts on the door beveled to snap over into engagement with the keepers, a rod connecting the bolts for movement in unison, an operating lever mounted on the door and connected with the rod, and a trip device arranged to engage one of the bolts, whereby the latter may be retracted independent of said rod.
